BUSHING EXTRACTING AND
INSERTING TOOL

Myron A. Hamman, Chicago, Ill.

Application August 7, 1935, Serial No. 35,113

5 Claims. (Cl. 29—88.2)

The invention relates to improvements in a screw press particularly adapted for extracting and inserting such articles as bearings, bushings, and the like. In this instance, however, 5 the invention contemplates a device or tool with which to perform the above mentioned operations quite readily and effectively by hand.

The invention further contemplates a tool, having the above stated characteristics, being 10 comparatively of light weight but so constructed as to withstand long and hard usage.

It is further contemplated to provide a tool, having the above stated characteristics, which may be constructed of, comparatively, few parts 15 with which to extract and insert various size articles of the above description with the least possible trouble and expense.

The invention further provides a device of the 20 above type which may be manufactured and marketed at, comparatively, a very small cost.

These and other objects of the invention will 25 be better understood by referring to the illustrations of the accompanying drawing, more fully described in the following specification, and more particularly pointed out in the appended claims.

In the illustrations, Figure 1 is, substantially, 30 a longitudinal sectional view showing the improvements embodied in the invention, and shows a bearing bushing about to be extracted from its place of installation to the position shown in light dotted lines, or after having been inserted in place.

Figure 2 is a similar sectional view of part of 35 the invention shown in Figure 1, and shows the tool in position for inserting a bearing bushing; and,

Figure 3 is a sectional view, on a smaller scale, taken on the plane 3—3, of Figure 1.

Similar characters refer to similar parts 40 throughout the several views.

To illustrate the invention I have shown on the drawing a jack screw holder or screw threaded nut 10, the same being, preferably, hexagonal 45 in cross section, and having screw threads 11, formed partially therethrough, the same being adapted to receive corresponding screw threads 11', of a forcing member or jack screw 12. The screw 12, is provided with a suitable bore 12', through which a draw bar or pull rod 14, is guided. Through a wall 10', formed at one end of holder 10, is formed, in this instance, a square opening 13, through which is workably fitted a square portion 14', of rod 14; the rod 14, being 50 turned round, as at 15, and provided with screw

threads 16, over which is fitted a double shouldered reversible adapter 17, having both its ends tapped with screw threads 17', to correspond with those formed on rod 14. The adapter 17, is adapted to engage a bearing bushing 18, for 5 either its removal or insertion, substantially as shown in Figures 1 and 2.

At the end 19, of holder 10, is provided a counterbore 20, into which is snugly fitted a tubular thrust member 21, the same being adapted to 10 receive an ejected bearing as indicated by light dotted lines in Figure 1.

Referring to Figure 1, it will be seen that jack screw 12, is provided with an enlarged portion or head 22, the same being provided with a counterbore 23, which is adapted to receive a suitable thrust bearing 24. The thrust bearing 24, is adapted to fit over rod 14, and between the bottom of counterbore 23, and the shoulder formed by the enlarged portion or head 25, provided on 20 the end of rod 14, as indicated in Figure 1. Radially out from head 22, and in opposite relation to each other, are arranged a pair of lever arms 26.

On desiring to remove a bushing or bearing 25 from its place of installation or bearing hub 27, rod 14, minus adapter 17, is inserted through the bushing 18, to the extent that member 21, engages the face of hub 27, and to the extent that portion 16, of rod 14, extends out beyond the 30 bushing as shown. The parts being in the position stated adapter 17, may now be threaded over portion 16, to the extent that it snugly engages and firmly clamps bearing and hub and part 21, together, whence the whole, that is the 35 tool, together with the part upon which hub 27, is formed, may be placed in a vice and there securely held between vice-jaws, being indicated by light dotted lines 28, as shown in both Figures 1 and 2.

The tool being in the position stated, and the 40 several parts being arranged as described, the bushing 18, may be readily withdrawn or ejected from its secured position simply by unscrewing jack-screw 12, from its holder 10, the operation 45 of which, by means of levers 26, engages the head 25, of rod 14, through the medium of thrust bearing 24, thereby forcing rod 14, to draw adapter 17, against the bushing forcing the same out from its bore to the position shown by light 50 dotted lines in Figure 1.

It may be stated, that owing to the fact that rod 14, is square, and is guided through a corresponding square opening 13, in holder 10, it will 55 not turn when ejecting or inserting a bushing,

therefore, there is no danger of adapter 17, being deranged while performing the operation of removing or inserting a bushing.

It may be further stated, that the operation of 5 inserting a bushing is substantially identical with that of removing or ejecting a bushing.

Having thus described the invention it can be readily understood that the minor details of its 10 construction may be altered in several ways without departing from the spirit and scope of the invention, and without losing any of its attendant advantages. Therefore, what is claimed 15 is desired to be secured by Letters Patent.

I claim:

15. 1. In a tool, of the character described, a jack-screw holder, a jack screw workable through said holder, a square draw rod or spline operable by means of said screw and slidably mounted in a central corresponding square opening provided 20 in said holder, a bushing ejecting or inserting reversible adapter detachably securable to one or free end of said rod, a thrust member carried by said holder, a thrust bearing interposed between said screw and a shoulder formed on one 25 end of said rod, and jack-screw operating handles suitably fastened in said screw.

2. In a tool, of the character described, a jack-screw holder, a jack-screw workable through said holder, a square rod for extracting or inserting 30 bearing bushings and the like slidably mounted for longitudinal movement through said holder, said rod having a shoulder formed at one of its ends and the opposite end thereof being provided with screw threads, a thrust bearing interposed between said shoulder and the said 35 jack-screw, a reversible or double-ended bushing ejecting or inserting adapter having its opposite ends tapped to receive the screw threaded end of said rod, and operating handles or levers secured 40 in said jack-screw.

3. A tool, of the character described, having a draw bar and a jack-screw for operating said bar, said bar being formed square, one end thereof being turned round and having screw 45 threads formed thereon, the opposite end being enlarged to form a head providing a shoulder, a thrust bearing arranged over said bar intermediate said shoulder and the said jack-screw,

said screw being adapted to workably fit over the square portion of said bar and form a bearing therefor, a holder or mounting having a screw threaded bore, said screw being adapted to workably fit said bore, and a square opening 5 formed in said holder, the said opening being adapted to form a guide or key-way through which the square portion of said bar may slide and be prevented from turning.

4. A tool, of the character described, having 10 a jack-screw and a holder in which to operate said screw, a wall formed in one end of the holder having an axial square opening formed there-through, said screw having a concentric circular bore formed there-through, said screw 15 being enlarged at one end to form a head portion, a counter-bore formed in said portion concentric to said bore the bottom of which forming a shoulder, a thrust bearing adapted to fit in said counter-bore and against said shoulder, 20 a square draw bar having a shoulder formed at its one end adapted to fit against said bearing, the said bar being adapted to slidably operate through said square opening, said circular bore being adapted to workably fit said draw bar, and 25 hand levers suitably secured in said head portion.

5. A tool, of the character described, having a jack-screw holder, said holder being provided with a screw-threaded bore, a jack-screw 30 adapted to workably fit the screw threads of said bore, said jack-screw having a counter-bore formed concentrically in its outer end the bottom of the counter-bore forming a shoulder, a wall formed in said holder, said wall having a 35 square opening formed axially there-through, a concentric counter-bore formed in the end of said holder, said counter-bore being adapted to receive a tubular thrust member, said square opening being adapted to form a guide for the 40 square portion of a draw-bar movably mounted therein, a draw-bar having a portion thereof formed square the same being adapted to slidably fit said square opening, an enlargement formed on one end of said bar providing a shoulder, and a thrust bearing loosely mounted over 45 said bar intermediate the said shoulders.

MYRON A. HAMMAN.
